UNITED STATES PATENT OFFICE.

ROBERT W. HARE, OF PITTSBURG, PENNSYLVANIA.

VERTICAL FOLDING FIRE-DOOR.

No. 889,005.

Specification of Letters Patent.

Patented May 26, 1908.

Application filed August 15, 1907. Serial No. 388,642.

To all whom it may concern:

Be it known that I, ROBERT W. HARE, a citizen of the United States of America, residing at Pittsburg, in the county of Allegheny and State of Pennsylvania, have invented certain new and useful Improvements in Vertical Folding Fire-Doors, of which the following is a specification, reference being had therein to the accompanying drawing.

This invention relates to improvements in folding fire doors, and the invention relates more particularly to an automatic closing folding fire door for elevator shafts, doorways, and other openings.

The invention has for its object to provide a novel safety device for confining and preventing the spread of fire in a building in which there is an elevator shaft, door ways or other openings tending to create a draft.

My invention aims to provide a novel vertically folding fire door that will occupy a comparatively small space above the doorway or opening to be closed by the door. It is generally the practice to use solid doors which require considerable space above the doorway or opening, when the door is opened, thus preventing the fire door from being used in a low compartment, or in a room where the door frame or opening extends in close proximity to the ceiling.

In constructing my improved door, I have aimed to provide a vertically moving door that can be easily and quickly folded to occupy a comparatively small space, and in connection with the door, I use novel means for temporarily holding the door, in a folded position, also means for quickly releasing the same and guiding the door into a closed position, should a fire occur in the vicinity of the door. To this end I construct the fire door of a plurality of vertically moving folding sections and employ weights as a counterpoise for the various sections, said counterpoise device being arranged to insure a positive operation and closing of the door in case of fire.

The detail construction entering into my invention will be presently described and then specifically pointed out in the appended claims.

Referring to the drawings, Figure 1 is a perspective view of a door constructed in accordance with my invention, Fig. 2 is a vertical sectional view of the door in an open

and folded position, and Fig. 3 is a similar view of the door in a closed position.

In the accompanying drawings, 1 designates a door-way or opening, and at the sides of the door-way are arranged metallic vertical bars 2, which are suitably secured to a wall 3 having the door-way or opening 1. The vertical bars 2 extend above the doorway and intermediate their ends have their front flanges 4 cut away, and bent outwardly to provide guide lugs 5. The vertical bars 2 serve functionally as guides for a vertically moving door comprising a weighted section 6, an intermediate section, 7 and a top section 8, said sections being hinged together, as at 9 and 10. The intermediate section 7 is hinged to the front edge of the weighted section 6, whereby the intermediate section can fold outwardly; while the top section 8 is hinged to the rear edge of the intermediate section, whereby the top section 8 can fold rearwardly.

The lower edge of the bottom section 6 is weighted, as at 11 and is provided with a transverse bar 12 having its ends protruding beyond the vertical sides of the section 6 and pierced, as at 14. Connecting with the pierced ends of the bar 12 are cables 15, said cables passing over grooved pulleys or sheaves 16, journaled in bearings 17 carried by the wall 3, said bearings and pulleys being arranged adjacent to the upper ends of the vertical guide bars 2. The free ends of the cables 15 are provided with weights 18, these weights assisting in counterbalancing the folding door, when in a raised or folded position. Connecting with one end of the bar 12 is a cable 19 passing over a revolute pulley or sheave 20 carried by the wall 3, said cable being connected to a weight 21 by a fusible soft metal link 22 of a conventional form, this link being susceptible to the action of heat, and melting to release the weight 21 in case of fire. The weight 21 with the assistance of the weights 18 fully counterbalance the door when the same is in a raised or folded position, but when the weight 21 is released, the weight of the section 6 of the door is sufficient to overcome the counterpoise of the weights 18 and to descend by gravity, straightening the sections of the door as will presently appear.

The top section 8 is connected by a cable 23 to a weight 24, said cable passing over revolute pulleys 25, carried by the wall 3,

above the door-way and the upper ends of the vertical guide bars 2. I simply employ the weight 24 to prevent the descent of the upper edge of the top section 8 until the bottom section 6 has traveled a pre-determined distance and has straightened the sections 7 and 8, at which time the descent of the door by gravity operating in excess of the counterpoise carries all the sections down and closes the door-way.

The bottom section 6 is of a greater width than the sections 7 and 8, and is guided in its movement at all times by the vertical guide bars 2. The sections 7 and 8 are of a less width than the section 6, whereby they can fold outwardly, but to guide said sections, when being moved, I provide the upper vertical edges of the section 8 with trunnions or pins 26, engaging the vertical guide bars 2.

Assuming that the weight 21 is released, the weighted section 6 immediately descends, while the upper edge of the top section 8 is temporarily held by the weight 24. As the section 6 descends, the edges of the intermediate section 7 strike the guide lugs 5, forcing the section 7 inwardly into vertical alinement with the section 6. This movement of the intermediate section tends to straighten the top section 8, and this top section is prevented from buckling by a flange 27 carried by the lower edge of the section 8, said flange engaging the top edge of the intermediate section 7, when the door is folded.

To limit the upward movement of the door, when it is being opened, and to insure the sections 7 and 8 folding, I arrange a stop or guard 28 at the upper ends of the vertical guide bars 2, said stop or guard being carried by the wall 3.

It is thought that the automatic operation of the fire door in case of fire will be readily understood from the above description, taken in connection with the drawings, and while I have not herein illustrated any securing means for the door in the closed position, it is obvious that any suitable locking device can be used to hold the door down to the floor or for holding it back against the frame of the door-way or opening 1.

Having now described my invention what I claim as new, is:—

1. In a fire door, the combination with a wall having an opening formed therein, of vertically disposed guide-bars arranged at the sides of said opening and having their front flanges cut away to provide outwardly extending guide lugs, a door movably mounted between said bars and comprising a weighted bottom section, an intermediate section and a top section, all hinged together, said intermediate and top sections being of a less width than said weighted section, weights for counter-balancing said door when in a raised position, a weight for

temporarily retarding the downward movement of said top section, and means for retaining said top section in engagement with said guide-bars.

2. A fire door comprising three hinged sections, guides secured to the wall or casing which said door closes, said guides being cut away to permit of two of said sections swinging outwardly, lugs carried by said guides for guiding one of said sections, weights counter-balancing said door when raised, a weight for temporarily retarding the movement of said sections when the door is closing, and means for limiting the upward movement of said door.

3. A fire door comprising a plurality of hinged sections, bars for guiding the movement of said sections, weights for counter-balancing said door when in a raised position, and a weight for retarding the closing movement of one of said sections.

4. A fire door comprising a plurality of horizontal hinged sections, two of said sections folding outwardly, guides for engaging two of said sections, lugs carried by said guides for engaging the other of said sections, means for temporarily holding said door in a raised and folded position, and means for temporarily retarding the movement of one of said sections when the first mentioned means is released.

5. A fire door comprising a plurality of hinged sections, two of said sections being adapted to fold outwardly, guides for engaging two of said sections, lugs carried by said guides for engaging the other of said sections, and means for temporarily holding two of said sections in a folded position.

6. A fire door comprising a weighted section, an intermediate section and a top section, guides for said weighted and top sections, means for temporarily holding said weighted section in an elevated position with the other of said sections folded, and means for temporarily retarding the movement of said top section when the first mentioned means is released.

7. A fire door comprising vertically moving hinged folding sections, means for temporarily holding said sections in a folded position, and means for retarding the movement of one of said sections when the first mentioned means is released.

8. A fire door comprising three hinged sections, two of said sections folding outwardly, means for temporarily retaining said sections in a folded position, means for guiding two of said sections, and means for retarding the closing movement of one of said sections.

9. In a fire door which closes an opening, and which is composed of the following elements in combination, namely;—the door sections hinged together, bars for guiding two of said sections and cut away to permit

of the folding movement of two of said sections,—mechanism for maintaining said door sections temporarily elevated, and mechanism for effecting a retardation of the closing movement of one of said sections.

10. A fire door comprising a weighted lower section, an intermediate section hinged to said weighted section, a top section hinged to said intermediate section, the top section and the intermediate section adapted to fold outwardly, means connected to the weighted section to normally hold all of the sections elevated with the top section and the intermediate section in folded position, guides for said sections in which the ends of the weighted section are received, and guide lugs carried by said guides to be engaged by the intermediate section as the door sections are lowered whereby the said intermediate section is forced into alinement with the weighted section.

11. A fire door comprising a weighted

lower section, an intermediate section hinged to said weighted section, a top section hinged to said intermediate section, the top section 25 and intermediate section adapted to fold outwardly, means connected to the weighted section to normally hold all of the door sections elevated with the top section and intermediate section in folded position, guides 30 for said sections in which the ends of the weighted section are received, and means carried by said guides to be engaged by the intermediate section as the door sections are lowered whereby the said section is 35 forced into alinement with the weighted section.

In testimony whereof I affix my signature in the presence of two witnesses.
